WHEELED BALANCING TOY

Joseph Fryer, Vancouver, British Columbia, and
 Colin Fitzgerald, West Vancouver, British Columbia, Canada

Application December 8, 1950, Serial No. 13,338

Term of patent 3½ years

(Cl. D34—15)

To all whom it may concern:

Be it known that we, Joseph Fryer, a citizen of Canada and a resident of the city of Vancouver, Province of British Columbia, Canada, and Colin Fitzgerald, a citizen of Canada and a resident of the municipality of West Vancouver, Province of British Columbia, Canada, have invented a new, original, and ornamental Design for a Wheeled Balancing Toy, of which the following is a specification, reference being had to the accompanying drawing, forming a part thereof.

Fig. 1 is a perspective view of a wheeled balancing toy, showing our new design; and

Fig. 2 is a front elevational view thereof.

The side of the toy not shown has substantially the same appearance as the side shown in Fig. 1.

The fragmentary dotted line showing of a supporting wire is for illustrative purposes only.

We claim:

The ornamental design for a wheeled balancing toy, as shown and described.

JOSEPH FRYER.
 COLIN FITZGERALD.
